UNITED STATES PATENT OFFICE.

ERNEST M. WHITE, OF DETROIT, MICHIGAN.

LUBRICATING SYSTEM FOR INTERNAL-COMBUSTION ENGINES.

1,224,694.

Specification of Letters Patent. Patented May 1, 1917.

Application filed July 31, 1916. Serial No. 112,229.

To all whom it may concern:

Be it known that I, ERNEST M. WHITE, a citizen of the United States, and residing at Detroit, in the county of Wayne and State 5 of Michigan, have invented a new and Improved Lubricating System for Internal-Combustion Engines, of which the following is a specification.

This invention relates to means for causing continuous and sufficient but not excessive lubrication of the pistons and crank shafts of internal-combustion engines and its object is to provide a series of oil receptacles from which the lubricant can be splashed up by the lower ends of the connecting rods; to prevent excessive depth of oil in these receptacles; to provide for the removal of the excess of the oil thus splashed up; and to provide for the conveying of the remainder 20 of the oil thus splashed up longitudinally of the engine.

This invention consists in a novel structure, preferably of sheet metal, mounted below and preferably parallel to the crank 25 shaft of a multi-cylinder internal-combustion engine, and having a series of lubricating oil receptacles into which the lower ends of the connecting rods or projections on such rods may dip to splash up the oil, in combination with means for feeding the lubricating oil to the two end receptacles; the structure being formed with openings, preferably on that side of the end receptacles toward which the connecting rods move as they dip 35 into the lubricant, through which openings the excess of the lubricating oil is thrown by the connecting rods, and with means for conveying the remainder of the splashed up oil longitudinally to the adjacent oil receptacles, said means being located on the opposite side of the central vertical plane of the engine from the openings for permitting the escape of part of the splashed up oil. It also consists in so forming the structure that the 45 oil in the receptacles will be at one depth when the engine is horizontal, at a greater depth when one end of the engine is elevated, and at a lesser depth when the same end of the engine is lowered.

50 In the accompanying drawings, Figure 1 is an elevation of an internal combustion engine provided with this improved lubricating system, a portion of the crank case being broken away so as to show the interior construction. Fig. 2 is a plan of the oil receptacles employed in the present invention.

Fig. 3 is a section of the lower part of the engine on the line 3--3 of Fig. 1. Fig. 4 is a plan of the oil receptacles of a four-cylinder engine.

Similar reference characters refer to like parts throughout the several views.

The engine which is conventionally shown in Fig. 1 has its cylinders cast in a block 4 which connects to the upper part of the crank 65 case. The lower part 5 of the crank case preferably connects to the upper along a plane horizontally below the axis of the crank shaft 6, to which the connecting rods 7, 8, 9, 10, 11 and 12 connect. The drawing 70 shows the front bearing 14, intermediate bearing 15 and rear bearing 17 for the crank shaft formed with oil cups 16 and oil holes 18.

The bottom 5 of the crank case constitutes 75 the main reservoir for the lubricating oil, which is drawn therefrom by means of any desired type of pump 19, a strainer 20 and foot valve 21 of any desired type being mounted at the lower end of the suction pipe 80 22 if desired. From the pump, discharge pipes 24, 25 and 26 extend to the bearings of the crank shaft in the usual manner, and the surplus oil from these bearings flows away through the passages 27, 28 and 29. 85 The parts thus far described are well known and by themselves, form no part of the present invention.

90 Mounted within the crank case is an oil pan 30, preferably of sheet metal, formed with a series of oil receptacles 31, 32, 33, 34, 35 and 36, one for each connecting rod. Connecting to each receptacle is a depression 37 which normally determines the height of the oil in the receptacles, all excess flowing down through the holes 38 into the main reservoir. These depressions extend forwardly from the receptacles, for when the engine is on an automobile going down hill, the work done by the engine is 100 below normal and the lubricant required is also less than when the vehicle is running on level roads. By forming the depressions at the front of the receptacles the oil will flow out until the level thereof is below normal and the amount splashed up by the connecting rods is also below normal.

105 When, however, the vehicle is climbing up hill, the elevated rear walls of the oil receptacles insure a larger amount of oil 110 being held in each receptacle and therefore a larger amount of lubricant is splashed up

at the time the engine is doing the hardest work.

In order to insure a proper amount of lubricant reaching the bearings, it is desirable to pump an excess of oil thereto, the excess running off through the passages 27, 28 and 29. This oil is then used to lubricate the connecting rods and pistons, being permitted to flow down the inclined edges 39 and 40 of the oil pan 30 to the end receptacles 31 and 36. At the front end of the oil pan a deflector 42 is shown to prevent the oil from the front bearing from flowing directly through the front passage 38. Oil from the bearing 15 will run down into the receptacles 33 and 34.

The amount of oil that enters the receptacles in the oil pan is usually much greater than necessary and it is therefore desirable to get a large portion of it to the main reservoir as soon as possible. The extensions or fingers 44 (Fig. 3) on the lower ends of the connecting rods strike the pools of oil in the receptacles with great force at high speed. The oil will be thrown out of the receptacles in the form of larger masses and drops and smaller drops or particles and the heavy masses and drops will be largely thrown out through the openings 46 or passages 46 and fall into the main reservoir. Some of the smaller drops will be thrown up into the cylinders while others will be thrown against both walls of the crank case and run down to the oil pan. The oil pan is shown provided with inclined oil troughs 47 that deliver the oil that runs down opposite the receptacles 32 and 35 respectively to these receptacles, and with troughs 48, 49 and 50, which convey oil splashed up from the receptacles 31 and 36 to the receptacles 32 and 35 respectively and oil splashed up from the last two to the inner receptacles 33 and 34. The opening 52 in the oil pan is for the suction pipe 22.

It will thus be seen that instead of the great excess of oil remaining in the receptacles 31 and 36 as it is received from the bearings, much of it will be thrown out through the openings 46 and that some will be carried entirely around with the connecting rod and be dashed against the opposite wall. This will be carried to the receptacles 32 and 35 which will be provided with sufficient oil at all times, the excess flowing away through the passages 38 adjacent thereto. The perfect distribution and the abstraction of all unnecessary oil makes for the most economical use of the lubricant and avoids the excessive deposit of carbon so often found in combustion chambers and on spark plugs and valves when an excess of oil is splashed up into the cylinders and there burned.

While Figs. 1, 2 and 3 disclose a lubri-

cating system for six-cylinder engines, Fig. 4 discloses an oil pan particularly adapted for four cylinder motors. The pan 60 has parallel receptacles 61, 62, 63 and 64 to hold the lubricant into which the ends of the connecting rods may dip. In this case again the larger drops of oil will be thrown out through the openings 65. The receptacles 61 and 64 receive the oil from the bearings and that which is splashed up and carried over against the opposite wall of the crank case and runs down will be caught by the inclined troughs 66 and flow to the adjacent receptacles 62 and 63. The oil that is splashed up out of the receptacles 62 and 63 and is carried over and flows down the side of the crank case between these receptacles will be caught by the troughs 67 and flow to the opening 68 and pass to the main oil reservoir.

Under some conditions, the heavy drops or masses of lubricant may be carried around by the cranks and the lower ends of the connecting rods. This will necessitate the positions of the openings 46 and 90 of the troughs 49 and 50 being reversed, the troughs 49 and 50 being on the side toward which the lower ends of the connecting rods are moving when they strike the lubricant in the receptacles in the oil 95 pan, and the openings 46 on the side from which such lower ends are moving.

While this lubricating system is shown especially adapted for four and six cylinder engines, it will be clear that it may be expanded or contracted as may be desired, and that the distance or direction of transfer of lubricant will depend entirely on the type of engine. The construction of the oil pan, its openings and conveyer troughs may 105 be modified by those skilled in the art to meet any problem without departing from the spirit of my invention as set forth in the followings claims:

I claim:

1. In a lubricating system for multi-cylinder engines, the combination of a crank case constituting the main oil reservoir and an oil pan within the crank case and formed with transverse oil receptacles, one for each connecting rod, said oil pan having depressions connecting to said receptacles, and openings in said depressions through which the oil can flow to the main reservoir, said oil pan also having openings in transverse alignment and at one side of a plurality of said receptacles, and inclined troughs on the opposite side from said last named openings to convey oil longitudinally of the crank case.

2. In a lubricating system for multi-cylinder engines, the combination of a crank case constituting the main reservoir for lubricating oil and an oil pan within the crank case formed with transverse oil receptacles,

- one for each connecting rod, means to convey lubricating oil to the two end receptacles, said oil pan having openings at one side of the central plane of the engine 5 through which oil may be thrown by the connecting rods as they dip into said receptacles, and inclined troughs on the opposite side of the oil pan to convey splashed up oil longitudinally of the crank case to 10 other receptacles.
3. In a lubricating system for multi-cylinder engines, the combination of a crank case constituting the main reservoir for lubricating oil and an oil pan within the crank 15 case formed with oil receptacles into which the connecting rods may dip to splash up the oil, said pan formed with openings through which the excess of splashed up oil may pass to the main reservoir; means to 20 convey a portion of the splashed up oil longitudinally of the crank case to other receptacles, and means to carry the oil from the main reservoir to one of the receptacles.
- 25 4. In a lubricating system for multi-cylinder engines, the combination of a crank case constituting the main reservoir for lubricating oil, and a structure mounted within the crank case formed with oil receptacles into which the connecting rods may dip to splash up the oil, said structure formed with a plurality of openings through 30 which the excess of oil splashed up by the connecting rods may pass to the main reservoir, and a series of troughs within said structure inclining inwardly to catch a portion of the oil splashed up from relatively

outer receptacles and convey it to the next adjacent receptacles.

5. In a lubricating system for multi-cylinder engines, the combination of a main reservoir for the lubricating oil, means to convey the oil from the reservoir to the bearings of the engine, a structure mounted in the crank case below the bearings of the engine and adapted to receive the oil that flows therefrom and formed with transverse depressions adapted to hold oil into which the connecting rods of the engine may dip to splash up the oil, means to convey a portion of the splashed up oil to the depression next inside the one from which the oil was splashed up, said structure formed to permit the passage of another portion of the splashed up oil directly to the 55 main reservoir.

6. In a lubricating system for multi-cylinder engines, the combination of a main reservoir for the lubricating oil, means to convey the oil from the reservoir to the bearings of the engine, a structure mounted in the crank case below the bearings of the engine and formed with transverse receptacles adapted to receive the oil that flows from said bearings and into which receptacles the connecting rods may dip to splash up the oil, and inclined troughs for conveying part of the oil splashed up from the outer bearings to the inner bearings, said structure being formed with openings to control the 65 level of oil in the receptacles and to permit the excess of splashed up oil to flow to the main reservoir.

ERNEST M. WHITE.
